UNITED STATES PATENT OFFICE.

MEILICH MELAMID, OF FREIBURG, BADEN, GERMANY.

METHOD OF PRODUCING PURE TAR DISTILLATES.

1,183,749.

Specification of Letters Patent.

Patented May 16, 1916.

No Drawing.

Application filed May 28, 1915. Serial No. 31,050.

To all whom it may concern:

Be it known that I, MEILICH MELAMID, a subject of the Czar of Russia, and residing at Freiburg, in the Grand Duchy of Baden, 5 German Empire, have invented a certain new and useful Method of Producing Pure Tar Distillates, of which the following is a specification, this application being a division in part of copending application Serial 10 No. 772,839, filed June 10, 1913, this latter application being a divisional application of my application for Letters Patent Serial No. 732,141, filed November 18, 1912.

In said former application, Serial No. 15 772,839, division of 732,141, I have described a process of treating tar with phosphoric acid. The products obtained by this process are ready for use without being first subjected to a refining or purification process.

20 This process may be carried out also in this way that another oxygen compound of phosphorus, for instance pyro-phosphoric acid, meta-phosphoric acid, phosphorus-pentoxid (P_2O_5) or phosphorous acid, or a 25 mixture of phosphoric acid with the named other phosphorus-oxygen compounds or a mixture of such compounds in any desired proportions is made use of.

The mode of execution of the process depends in some measure upon the origin of the tar; one way is the following: 1000 kg. tar is well mixed with 10 kg. pyro-phosphoric acid, after mixing, the mass is heated and distilled. Or 100 kg. tar is well 35 mixed with 50 kg. ortho-phosphoric acid, 10 kg. pyro-phosphoric acid, 10 kg. phosphorous acid, 10 kg. meta-phosphoric acid, 5 kg. phosphorus-pentoxid (P_2O_5), after mixing, the mass is heated and distilled. Or 40 1000 kg. tar is mixed with 50 kg. HPO_4 , and 50 kg. $NaPO_4$, after mixing the mass is heated and distilled. Or 1000 kg. tar is mixed with 50 kg. pyro-phosphoric acid, 10 kg. phosphorous acid and 30 kg. 45 meta-phosphoric acid, after mixing, the mass is heated and distilled.

Preferably a heat of 150-200° C. is employed in executing my process in practice according to the above examples.

50 The process instead of being applied to

tar, can be applied to tar-oils or tar-distillates.

What I claim as new and desire to secure by Letters Patent of the United States is:

1. The process of producing pure distillates from tar, tar oils and hydrocarbons contained in the tar, consisting in heating tar, tar oils and hydrocarbons contained in the tar with a phosphorus-oxygen-compound other than ortho phosphoric acid, 55 substantially as described.

2. The process of producing pure distillates from tar, tar oils and hydrocarbons contained in the tar, consisting in heating tar, tar oils and hydrocarbons contained in 65 the tar with a mixture of phosphorus-oxygen-compounds, not containing ortho phosphoric acid, substantially as described.

3. The process of producing pure distillates from tar, tar oils and hydrocarbons 70 contained in the tar, consisting in bringing together tar, tar oils, and hydrocarbons contained in the tar with a phosphorus-oxygen-compound other than ortho phosphoric acid and heating the mixture to a 75 low temperature, substantially as described.

4. The process of producing pure distillates from tar, tar oils, and hydrocarbons contained in the tar, consisting in bringing together tar, tar oils, and hydrocarbons 80 contained in the tar with a phosphorus-oxygen-compound other than ortho phosphoric acid and heating the mixture to approximately 150-200° C., substantially as described. 85

5. The process of producing pure distillates from tar, tar oils, and hydrocarbons contained in the tar, consisting in bringing together tar, tar oils, and hydrocarbons contained in the tar with several phosphorus-oxygen-compounds other than ortho phosphoric acid and heating the mixture to approximately 150-200° C., substantially as described. 90

In testimony whereof I affix my signature 95 in presence of two witnesses.

DR. MEILICH MELAMID.

Witnesses:

HERMANN METZGER,
ADOLF DECK.
